UNITED STATES PATENT OFFICE.

ANDREW J. SANFORD, OF NEWARK, OHIO, ASSIGNOR TO A. H. HEISEY & CO., OF NEWARK, OHIO.

DESIGN FOR A DISH.

48,614.

Specification for Design.

Patented Feb. 22, 1916.

Application filed November 19, 1915. Serial No. 62,430. Term of patent 14 years.

To all whom it may concern:

Be it known that I, ANDREW J. SANFORD, a citizen of the United States, residing at Newark, Ohio, have invented a new, original, and ornamental Design for a Dish, of which the following is a specification, reference being had to the accompanying drawing, forming a part thereof.

In the drawing: Figure 1 is a bottom plan, and Fig. 2 is a side elevation of the dish embodying my invention.

I claim:—

The design for a dish, substantially as shown.

ANDREW J. SANFORD.

Witnesses:

MAUD BOTT,
C. E. DILLON.
